UNITED STATES PATENT OFFICE

149,032

DESIGN FOR A CANDLESTICK

Michael Vozzella, Malden, Mass.

Application December 4, 1946, Serial No. 135,256

Term of patent 7 years

(Cl. D48—20)

To all whom it may concern:

Be it known that I, Michael Vozzella, a citizen of the United States of America, residing at Malden, in the county of Middlesex and State of Massachusetts, have invented a new, original, and ornamental Design for a Candlestick, of which the following is a specification, reference being had to the accompanying drawings, forming part thereof.

I claim:

The ornamental design for a candlestick, as shown.

MICHAEL VOZZELLA.
